UNITED STATES PATENT OFFICE.

ANTHONY J. STUMPF, OF CHICAGO, ILLINOIS.

DESIGN FOR A VEHICLE-BODY.

53,668.

Specification for Design.

Patented July 29, 1919.

Application filed August 29, 1918. Serial No. 251,997. Term of patent 7 years.

To all whom it may concern:

Be it known that I, ANTHONY J. STUMPF, a citizen of the United States, residing at Chicago, in the county of Cook and State of Illinois, have invented a new, original, and ornamental Design for Vehicle-Bodies, of which the following is a specification, reference being had to the accompanying drawing, forming a part thereof.

In the drawing, the figure is a side view of a vehicle body, showing my new design.

I claim:

The ornamental design for a vehicle body, as shown.

ANTHONY J. STUMPF.
